AUTOMATIC SELF-CENTERING GUIDE EYE

John J. Dunleavy, Scranton, Pa.

Application August 4, 1937, Serial No. 157,443

14 Claims. (Cl. 242—157)

This invention relates to thread guiding devices such as are used in the textile art in connection with various types of winding machines.

The principal object of the invention is the provision of a self-centering guide used in connection with the winding of yarn and thread, principally silk and rayon yarn, and by the use of which pile yarn windings at the spool heads are eliminated.

10 A further object is the provision of an automatic self-centering guide eye provided with a projecting feeler arm which when it contacts with the spool head releases the guide eye member from the action of the traverse bar and wherein the guide eye is again automatically connected to the traverse bar and properly centered.

15 A further object is the provision of a self-centering automatic guide eye by the use of which a more even wind is obtained through the winding of thread or yarn particularly silk or rayon yarn and wherein any bulging of the yarn at the heads of the spools is eliminated.

20 A further object is the provision of a device of this character wherein a more even tension with a better wound spool of yarn or thread is attained and wherein in operation the yarn is in contact only with the usual standard porcelain guide eye carried by the guide eye clamp or holder.

25 A further object is the provision of a device of this character wherein proper centering of the yarn is always maintained and piling up of the yarn at the head of the spool is prevented.

30 Heretofore in guides of this character in this art it has first been necessary to ascertain the proper position and location of the guide on the traverse rail and after such position is ascertained the guide is adjusted along the traverse guide rail and set and remains fixed during the operation of winding.

35 My invention is the first wherein is provided an automatic self-centering guide eye for use in winding yarn or thread in winding machinery.

40 My self-centering guide eye is shown in the accompanying drawing, wherein corresponding reference numerals are used to indicate corresponding parts in each of the several views.

In the drawing:—

45 Fig. 1 is a plan view of my device showing same attached to the traverse rail and as used in connection with the spool on which the yarn is being wound;

Fig. 2 is a rear face view of the device;

Fig. 3 is an end view;

50 Fig. 4 is a front elevation;

Fig. 5 is a sectional view on the line 5—5 of Fig. 4; and

Fig. 6 is a detailed perspective view of the device.

The thread or yarn 10 being wound on the spool A, passes through the slot or notch 11 in the usual thread guide 12, of porcelain or the like. This thread guide 12 is securely clamped in the plate 13. The plate 13 has formed on its rear edge, from the metal of the plate, a loop or socket 14, through which is passed a pin or rod 15. The base plate 16 is rigidly secured to the traverse rail 17 by means of screws or other fastenings 18a, so that the guide 12 is caused to move with the traverse rail, in both directions. On the inner edge of the plate 16 at each end is provided a loop or socket 14a which carries the pin 15. The loop or socket 14 is shorter than the distance between the loops 14a to allow for a sliding or lengthwise movement or play of the guide 12 when the feeler arm or projection 21 contacts the head 24 or 25 of the spool. Projecting downwardly from the plate 13 from the front thereof is a portion 18 formed from the metal plate. The lower edge of this downwardly projecting portion is provided with teeth or indentations 19 in which enter upwardly extending projections or teeth 20 on the base 16.

It will thus be seen that when the teeth 20 are in mesh with the teeth 19, the guide eye will be carried along with the traverse rail in whichever direction the same is moving.

Projecting inwardly from the portion 18 is a feeler arm or projection 21 which, in the present instance is made adjustable as to its length by passing the inner end of the arm through an opening in the plate 18 and downwardly extending portion 22 of the plate 13. A spring 23 is interposed between the plates 22 and 18 which normally holds the arm 21 projected outwardly.

The feeler arm 21 is made adjustable in order to take care of filled or partially filled spools and is automatically shortened as the mass of yarn on the spool increases.

It will thus be seen that when the feeler arm 21 contacts with the head 24 or 25 of the spool, the spool revolving, due to friction the guide with its clamp will be pivotally moved on the pin or rod 15 and released from the plate 16, which is carried by the traverse rail, and moved along the rod, and automatically returned by gravity, into proper centering position, when it will drop and again mesh with the teeth 20 and when the traverse rail starts in the opposite direction and reaches the head 25 of the spool, if piling of the

yarn is likely to occur, the same operation will be performed and the same action take place.

It will thus be obvious that by the action of my self-centering automatic guide and the operation thereof, piling yarn windings at the spool heads will be eliminated.

Having thus fully described my invention, what I claim as new and desire to secure by Letters Patent of the United States, is:—

- 10 1. In a device of the character described, a traverse guide rail, a self-centering guide eye pivotally and slidably mounted thereon and movable therewith, means normally holding said guide eye against sliding movement on the rail, a winding spool for the yarn, and means adapted to contact with the head of the spool and cause said guide eye to swing on its pivot and thereby automatically disconnect said guide eye from movement with the rail.
- 20 2. In a device of the character described a traverse guide rail, a winding spool, a self-centering guide eye slidably and pivotally mounted on the rail and movable therewith, means holding said guide eye against sliding movement on the rail, a contact arm on the guide eye adapted to contact with the head of said spool and automatically disconnect the holding means to permit of relative movement between the rail and the guide eye.
- 30 3. A device of the character described for winders, comprising a thread guiding member, a plate, means carrying said thread guiding member pivotally and slidably mounted on said plate, means on said first mentioned means cooperating with means on said plate for normally holding said thread guiding member against sliding movement on the plate, and means for releasing said holding means to permit of relative movement between the plate and thread guiding member.
- 40 4. In a device of the character described, a traverse guide rail, a winding spool, a self-centering guide eye slidably and pivotally mounted on the rail and movable therewith, means for normally holding said guide eye for movement with the rail, an adjustable feeler or contact arm on the guide eye, said contact arm adapted when contacting a flange of the spool to release the guide eye and its holding means from the rail and permit of relative longitudinal movement of the guide eye and rail.
- 50 5. In a device of the character described, a traverse guide rail, a winding spool, a self-centering guide eye slidably and pivotally mounted on the rail and movable therewith, means for normally holding said guide eye for movement with the rail, an adjustable spring pressed contact arm on the guide eye adapted when contacting a flange of the spool to release the guide eye and its holding means from the rail and permit of relative longitudinal movement of the guide eye and rail.
- 60 6. In a device of the character described, a traverse guide rail, a plate for attachment thereto, teeth on said plate, a guide eye, a clamp carrying said guide eye pivoted to said plate and slidably thereon, said clamp being provided with teeth or serrations coacting with the teeth on the plate and capable of being swung on said pivot away from the plate.

7. In a device of the character described, a traverse guide rail, a self-centering guide eye pivotally and slidably mounted thereon and movable therewith, means normally holding said guide eye against sliding movement on the rail, and means for releasing said holding means to permit of relative movement between the rail and guide eye.

8. A device of the character described, for use in winders, comprising a guide eye, a plate for attachment to the traverse rail, the guide eye being pivotally and slidably mounted on the plate.

9. A device of the character described, for use in winders, comprising a guide eye, a plate for attachment to the traverse rail, the guide eye being pivotally and slidably mounted on the plate, and means for holding said guide eye and plate against longitudinal or sliding movement relative to each other.

10. A device of the character described, for use in winders, a winding spool, a guide eye, a plate for attachment to the traverse rail, the guide eye being pivotally and slidably mounted on the plate, means for holding said guide eye and plate against longitudinal or sliding movement relative to each other, and contact means on said guide eye adapted when contacting a flange of the spool of the winder to release the holding means and permit relative movement of the guide eye and plate.

11. In a device of the character described, a traverse guide rail, a winding spool, a self-centering guide eye slidably and pivotally mounted on the rail and movable therewith when in normal position, means for normally holding said guide eye for movement with the rail, means on the guide eye adapted to contact with the head of said spool and automatically swing the guide eye and its holding means on its pivot and thereby permit of sliding movement of the eye relative to the rail.

12. In a device of the character described, a traverse guide rail, a winding spool, a self-centering guide eye slidably and pivotally mounted on the rail and movable therewith when in normal position, means for normally holding said guide eye for movement with the rail, and adjustable means on the guide eye adapted to contact with the head of the spool and automatically swing the guide eye and its holding means on its pivot and thereby permit of sliding movement of the eye relative to the rail.

13. A centering guide eye for winders, comprising a plate adapted for attachment to a traverse guide rail, teeth on said plate, and a clamp for holding the eye pivoted to said plate and slidably thereon, said clamp provided with teeth or serrations coacting with the teeth on the plate whereby the clamp and plate are caused to move as a unit when in normal position, and means on said clamp for disengaging the teeth and thereby permitting relative movement of the clamp and plate.

14. A device of the character described for use in winders, comprising a plate, a pin mounted thereon, and a guide eye pivotally and slidably mounted on said pin.

JOHN J. DUNLEAVY.
